(57) **CLAIM**

The ornamental design for an embedded lighting workspace terminal unit, as shown and described.

DESCRIPTION

FIG. 1 is a bottom isometric view of an embedded lighting workspace terminal unit showing our new design.

FIG. 2 is a top isometric view thereof.

FIG. 3 is a front elevation view thereof.

FIG. 4 is a rear elevation view thereof.

FIG. 5 is a left elevation view thereof.

FIG. 6 is a right elevation view thereof.

FIG. 7 is a bottom plan view thereof; and,

FIG. 8 is a top plan view thereof.

The broken lines depicted in FIGS. 1-6 and 8 form no part of the claimed design.

1 Claim, 6 Drawing Sheets
